FRED E. ASELTINE, OF DAYTON, OHIO, ASSIGNOR TO DELCO PRODUCTS CORPORATION,
OF DAYTON, OHIO, A CORPORATION OF DELAWARE

CHARGE FORMING DEVICE

Application filed September 7, 1929. Serial No. 391,058.

This invention relates to charge forming devices for internal combustion engines of the type comprising a plurality of primary carburetors, which deliver a primary mixture of fuel and air to a plurality of secondary mixing chambers located adjacent the engine, intake ports and in which the primary mixture is mixed with additional air under certain operating conditions; and more particularly, to the manifold which forms a part of such charge forming device.

A device of this general character is disclosed in the copending application of Fred E. Aseltine, Wilford H. Teeter and Carl H. Kindl, Serial No. 288,683, filed June 27, 1928.

It is the principal object of the present invention to provide a device of this character which is effective to supply a more homogeneous mixture than has been possible with earlier forms of such devices, and which is effective under all operating conditions to secure equal distribution of such mixture to the various engine intake ports, particularly during the acceleration period following any opening movement of the throttle.

It is a more specific object of this invention to provide an intake manifold which conveys the air and fuel mixture to the engine intake ports with means for increasing the velocity of flow of the fuel mixture through the manifold without materially restricting the passage therethrough at open throttle position whereby better distribution of such mixture is secured with substantially no reduction in the volumetric efficiency of the engine.

Further objects and advantages of the present invention will be apparent from the following description, reference being had to the accompanying drawings wherein a preferred embodiment of one form of the present invention is clearly shown.

In the drawings:

Fig. 1 is a plan view of a charge forming device constructed in accordance with the present invention.

Fig. 2 is a vertical, longitudinal section through the charge forming device on the line 2—2 of Fig. 1.

Fig. 3 is a fragmentary, transverse section on the line 3—3 of Fig. 2.

Fig. 4 is a fragmentary, front elevation of the manifold showing the inlet which is adapted to communicate with the carburetor unit.

Fig. 5 is a section through the manifold on the line 5—5 of Fig. 1.

The device disclosed comprises a main air manifold 10, having three outlet branches 12, 14 and 16. Each of these branches communicate with one of the intake ports of a multi-cylinder engine and each is provided with an attaching flange 18 for securing the manifold to the engine block in the usual manner, while flange 20 to which the carburetor unit is secured is formed at the inlet of the manifold.

The carburetor unit comprises a main housing 22, having an attaching flange 24, adapted to be secured to the flange 20 by screws 26. An air inlet coupling 28 is secured in position to register with an opening in the upper wall of the housing 22 in any suitable way and may be connected with an air cleaner if desired. A casting 30, in which the passages supplying fuel to the nozzles 70 are formed, is secured by screws to the lower wall of the housing 22, and a sheet metal fuel bowl 32 is held tight against an annular shoulder 34 on the housing by any suitable means. Fuel is conducted from a main source of supply to the fuel bowl through a conduit (not shown) and the flow of fuel to the bowl is controlled by a float 36 operated in the usual manner to maintain a substantially constant level of fuel therein.

Fuel flows from the bowl 32 to a plurality of primary fuel nozzles 38, one of which is located in each of the primary mixing chambers 40, the construction of which is briefly described hereinafter. The fuel conduit be-

- 5   between the fuel bowl and the nozzles comprises a vertical fuel passage 42 communicating at its upper end with a horizontal fuel canal 44, which connects with each of the nozzles 38 through an orifice 46. Fuel is admitted from the fuel bowl to the passage 42 at all engine speeds through a fixed metering orifice 48, and at high speeds, additional fuel is admitted through an orifice 50, controlled by a valve 52 operated in the manner set forth in the above mentioned application. This operating means forms no part of the present invention and need not be described further herein.
- 10   15   Fuel is lifted from the fuel bowl through the above described fuel passages and nozzles 38 to the primary mixing chambers by the suction therein. Opening movements of the throttle cause a reduction in the mixing chamber suction which might permit the fuel column to drop sufficiently to cause a temporary fuel starving of the engine unless means are provided to prevent this action. For this purpose a check valve 54 is provided in an enlarged chamber 56 at the junction of the channels 42 and 44 and on reduction of the mixing chamber suction, seats on the bottom of said chamber and prevents downward flow of fuel.
- 20   25   30   Each nozzle is provided with a main fuel outlet 58 in the top of the nozzle, and a secondary fuel outlet comprising two orifices 60 and 62 in the vertical wall of the nozzle near the bottom of the mixing chamber. At relatively high speeds, the mixing chamber suction is sufficient to lift fuel from the main outlet as well as from the orifices 60 and 62. At idling, or low speed operation under load, however, the suction is enough to lift fuel only to some point between the top of the nozzle and the orifices 60 and 62, fuel flowing from these orifices by the action of gravity under such operating conditions. Each nozzle is provided with a restricted fuel metering orifice 63.
- 35   40   45   The primary mixing chambers comprise the enlarged anterior ends of the primary mixture passages 64, which are parallel to each other and close together, as indicated in Fig. 3. When the carburetor is attached to the manifold, these passages communicate with conduits conveying the primary mixture to the secondary mixing chambers, as fully described hereinafter. Restrictions 66 separate the primary mixing chambers from the remainder of the mixture passages to reduce the velocity of flow past the fuel nozzles for the purpose fully set forth in the above mentioned co-pending application.
- 50   55   60   A single throttle valve 68 which extends across all of the primary mixture passages, controls the flow therethrough and is provided with grooves 70, which register with said primary mixture passages. The throttle 65 is operated in the manner hereinafter more

fully described and serves not only to control the flow through the passages 64, but also to open and close air passages 71, which admit air to the primary mixture passage in advance of the restrictions 66 for the purpose 73 fully described in said earlier application.

Nearly all of the air entering the carburetor flows through the coupling 28 and is controlled by a main air valve 74, normally held against a seat 76, by a spring 78, received between the valve and flange 80, projecting from a sleeve 82, slidably mounted on a stationary guide sleeve 84, fixed in the main housing and serving also as a guide for the stem 86, to which the air valve is secured. When it is desired to choke the carburetor to aid in starting, the flange 80 is adapted to be lifted by means not shown herein but fully described in the above application, until the upper end of the sleeve 82 engages the air valve to hold it closed. Sufficient air to carry the starting fuel from the nozzles to the cylinders is admitted through an elongated slot 87, formed in a plate 88, secured to the housing 22, as shown in Fig. 2.

The valve 74 admits air to the air chamber 90 from which air flows to the primary mixture passage through an orifice 92 in the bottom of the air chamber and to the secondary mixing chambers through a passage 94, which connects with the inlet of the manifold 10. The flow of air through this passage is controlled by a manually operable throttle 96, secured to a shaft 98, rotatably mounted in the housing 22, and by a suction operated valve 100, fixed on a shaft 102, also rotatably mounted in the main housing.

The specific operating connections for the two throttle valves form no part of the present invention and are not described herein, it being sufficient for the purposes of this disclosure to describe briefly the mode of operation of these valves. The primary throttle is connected to the valve 96 by a lost motion connection which permits a certain predetermined movement of the primary throttle independent of said valve 96. The lost motion connection may be adjusted and in general practice is so adjusted that the primary throttle may be moved without accompanying movement of the valve 96 until the former reaches a position corresponding to a vehicular speed of approximately 15 to 20 miles per hour on the level. On further opening of the primary throttle, the air throttle is moved simultaneously therewith.

On opening of one or both of the throttle valves, the suction in the air chamber 90 is increased and the valve 74 is opened to admit additional air and increase the quantity of mixture supplied to the engine. The opening of this valve is retarded to prevent fluttering of the valve and to prevent temporary leaning of the mixture immediately following an opening movement of the throttles.

For this purpose a dashpot is provided comprising a cylinder 104, which receives fuel from the reservoir 32, and a piston 106, secured to the lower end of the valve stem 86 by any suitable means. A check valve is provided in the bottom of the dashpot, as shown in the earlier application, to prevent the escape of fuel therefrom when the valve is open and to permit fuel to flow thereto on closing movements of the valve. The specific construction of this dashpot is not material so far as the present invention is concerned, and it may be of any conventional form which will properly retard the opening of the air valve.

As hereinbefore stated, the valve 100 is opened by engine suction when the air throttle 96 is opened. In certain earlier devices of this type, a dashpot has been provided for the purpose of retarding the opening of this valve. The purpose of this dashpot and its construction are fully described in the prior application, but its function is briefly set forth here in order to facilitate a clearer understanding of the present invention. If the valve 100 were permitted to open freely, the air admitted through the passage 94 would reach the secondary mixing chambers before the increased quantity of primary mixture, resulting from the opening of the throttle, and the mixture formed in the secondary mixing chambers would, therefore, be too lean temporarily to properly operate the engine immediately following any opening of the throttle. By retarding the opening of the valve 100, the time required for the air supplied through the passage 94 to reach the secondary mixing chambers becomes substantially that required for the increased supply of primary mixture to reach said chambers.

In order to enrich the primary mixture on opening movements of the throttle, the above described dashpot is constructed to operate as a fuel pump. To this end a fuel delivery conduit 110 connects with the bottom of the dashpot cylinder and extends to a horizontal passage 112, formed in a distributor block 114, secured to the lower face of the main housing in any suitable manner. The channel 112 communicates with three vertical channels 116, one of which is shown in Fig. 2, which in turn communicate with passages 118 formed in the wall of the main housing and communicating with each of the mixture passages. Passages 120 are formed within the block 114 and admit air from the space above the fuel in the reservoir 32 to the channel 112 to form an emulsion of fuel and air which is drawn into the primary mixture passages through the passages 116 and 118 in the manner fully described in the earlier application above referred to.

It has been found difficult to secure sufficient velocity of flow through the primary

mixture passages to secure proper fuel distribution and enable satisfactory engine operation when operating at intermediate speeds with the valves 96 and 100 partially open, particularly during the acceleration period immediately following any opening of the throttle, even by retarding the opening of the valve 100, as previously described. Where the air passing such valve is permitted to flow through the entire area of the manifold conduit, the velocity of flow therethrough must be relatively small at any but relatively high engine speeds with wide open throttle. There is, therefore, insufficient velocity of flow past the ends of the primary mixture conduits to create enough velocity in said conduits to supply sufficient fuel to form a mixture of proper proportions unless some passage restricting means is employed within the manifold branches to increase the velocity of flow past the ends of the primary mixture conduits, such for instance, as the Venturi tubes employed in the device disclosed in the above mentioned application. Passage restricting means of this character are objectionable because they reduce the volumetric efficiency of the engine at wide open throttle. According to the present invention, means have been provided to increase the velocity of flow through the primary mixture conduits whenever the valve 96 is opened without materially restricting the area of the main conduit through the manifold.

For this purpose the manifold is provided with a partition 130 formed therein when the manifold is cast and extending from a point substantially adjacent the inlet of said manifold through the lateral branches of the manifold numbered 132 and 134 and through all of the outlet branches 12, 14 and 16 of said manifold. This partition divides the manifold into two passages, 136 below the partition, and 138 above said partition, both of these passages communicating with the passage 94 in the carburetor unit. The passage 136 is always open so that any air passing through the passage 94 may flow into the passage 136, and through such passage to the intake ports.

The passage 138, on the other hand, is normally closed by a suction operated valve 140, which is secured to a shaft 142 positioned off center with respect to the valve and rotatably mounted in the manifold wall. The upper edge of the valve is adapted to engage a fixed stop 144 and is normally held in closed position in engagement with said stop by a tension spring 146, one end of which is connected to a lug 148, projecting within the passage 138 and the other end to a pin 150 projecting from the shaft 142. The passage 136, as above stated, is in communication with the passage 94 at all times and air will pass through the passage 136 whenever the valves

96 and 100 are open. The spring 146 which holds the valve 140 closed, resists the opening of the valve 140 to a greater degree than opening of valve 100 is opposed so that the 5 valve 140 does not open until the valve 100 is opened relatively wide and the engine is running at relatively high speed.

As previously stated, passages 64 communicate with conduits for conveying the primary mixture to the passage 136 in the various outlet branches of the manifold. These conduits include passages formed in the manifold casting, there being a straight passage 152 in the middle which communicates 10 directly with the passage 136 formed in the middle outlet branch of said manifold, and two outer passages 153 which are angular in form, as indicated in dotted lines in Fig. 1, and communicate with tubes 154. Those 15 are connected at their opposite ends to elbows 156, which in turn communicate with passages in end branches 12 and 16 of the manifold similar in form to the passage 152 previously described and communicating 20 with the passages 136 in each of said branches.

The operation of this device should be obvious. When the primary throttle alone is open, all the mixture passes through the primary mixture conduits and no air through 25 passage 136. As the speed of the engine is somewhat increased and the valves 96 and 100 are partially opened, as in the intermediate speed range, the valve 140 remains closed and 30 all of the fuel flowing to the secondary mixing chambers flows through the passage 136, and of course, at a considerably greater velocity than would be the case if the manifold consisted of one enlarged passage only. At 35 still higher engine speeds the valve 140 begins to open and gradually opens wide as the throttle approaches wide open position. It will be clear, therefore, that at all times the velocity of air past the primary mixture conduits is greater than in earlier forms of this 40 device and where no fixed restriction is provided, such as a Venturi tube, the volumetric efficiency of said engine is not reduced during operation at any speed.

45 While the form of embodiment of the present invention as herein disclosed, constitutes a preferred form, it is to be understood that other forms might be adopted, all coming within the scope of the claims which follow.

50 55 What is claimed is as follows:

1. A charge forming device for internal combustion engines comprising an intake pipe communicating with the engine intake port, a primary mixture passage delivering 55 a mixture of fuel and air to said pipe, means for supplying fuel and air to said mixture passage, means for accelerating the flow at the point of delivery of the primary mixture passage comprising means for dividing the intake pipe into two passages and means for

controlling the flow through one of said passages.

2. A charge forming device for internal combustion engines comprising a primary mixture passage, means for supplying fuel and air thereto, an intake pipe communicating with the engine intake port, means dividing said intake pipe into two passages into one of which the primary mixture passage delivers fuel mixture and means controlling the flow through one of said passages. 70

3. A charge forming device for internal combustion engines comprising a primary mixture passage, means for supplying fuel and air thereto, an intake pipe communicating with the engine intake port, means dividing said intake pipe into two passages into one of which the primary mixture passage delivers fuel mixture and means for normally preventing flow through the other of said passages. 75

4. A charge forming device for internal combustion engines comprising a primary mixture passage, means for supplying fuel and air thereto, an intake pipe communicating with the engine intake port, means dividing said intake pipe into two passages into one of which the primary mixture passage delivers fuel mixture and a suction operated valve in one of said passages for regulating the flow therethrough. 80

5. A charge forming device for internal combustion engines comprising a primary mixture passage, means for supplying fuel and air thereto, an intake pipe communicating with the engine intake port, means dividing said intake pipe into two passages into one of which the primary mixture passage delivers fuel mixture and a normally closed suction operated valve in one of said passages adapted to be opened at relatively high engine speeds. 95

6. A charge forming device for internal combustion engines comprising a primary mixture passage, means for supplying fuel and air thereto, an intake pipe communicating with the engine intake port, means dividing said intake pipe into two passages into one of which the primary mixture passage delivers fuel mixture, means for normally preventing a flow through the other of said passages, and means for rendering said flow preventing means ineffective at relatively high engine speeds. 100

7. A charge forming device for internal combustion engines comprising a carburetor unit provided with means for forming a primary mixture of air and fuel and a manifold associated therewith having a plurality of outlet branches adapted to supply a combustible mixture to the engine intake ports, each of said branches having a plurality of air passages formed therein and means for delivering the primary mixture to one of said passages. 110

8. A charge forming device for internal combustion engines comprising a carburetor unit provided with means for forming a primary mixture of air and fuel and a manifold associated therewith having a plurality of outlet branches adapted to supply a combustible mixture to the engine intake ports, each of said branches having a plurality of air passages formed therein, means for delivering the primary mixture to one of said 10 passages, and means for admitting air only to another of said passages.
9. A charge forming device for internal combustion engines comprising a carburetor unit provided with means for forming a primary mixture of air and fuel and a manifold associated therewith having a plurality of outlet branches adapted to supply a combustible mixture to the engine intake ports, each of said branches having a plurality of air 15 passages formed therein, means for delivering the primary mixture to one of said passages, means for admitting air only to another of said passages and a valve therein for controlling the flow of air therethrough.
10. A charge forming device for internal combustion engines comprising a carburetor unit provided with means for forming a primary mixture of air and fuel and a manifold associated therewith which is adapted to supply a combustible mixture to the engine intake ports, said manifold having a plurality of passages formed therein, means for delivering the primary mixture to one of said 20 passages, normally closed means for admitting air only to another of said passages and means for rendering said last mentioned means effective after a predetermined engine speed is reached.
11. A charge forming device for internal combustion engines comprising a carburetor unit provided with means for forming a primary mixture of air and fuel and a manifold associated therewith which is adapted to supply a combustible mixture to the engine intake ports, said manifold having a plurality of 25 passages formed therein, means for delivering the primary mixture to one of said passages, means for admitting air to said passages during operation at intermediate and high speeds and for admitting air to another of said passages only during operation at high speeds.
12. A charge forming device for internal combustion engines comprising a carburetor unit provided with means for forming a primary mixture of air and fuel and a manifold associated therewith which is adapted to supply a combustible mixture to the engine intake ports, an air inlet for supplying air to said manifold, and a plurality of passages 30 formed in said manifold, one of said passages being in communication with said air inlet at all times, and means adapted to effect communication between the air inlet and another 35 of said passages only at speeds above a predetermined speed.
13. A charge forming device for internal combustion engines comprising a carburetor unit provided with means for forming a primary mixture of air and fuel and a manifold associated therewith which is adapted to supply a combustible mixture to the engine intake ports, an air inlet for supplying air to said manifold, a plurality of passages 40 formed in said manifold, one of said passages being constantly open, a valve in the other of said passages to regulate the flow therethrough, and means for delivering the primary mixture to the constantly open passage.
14. A charge forming device for internal combustion engines comprising a carburetor unit provided with means for forming a primary mixture of air and fuel and a manifold associated therewith which is adapted to supply a combustible mixture to the engine intake ports, an air inlet for supplying air to said manifold, a plurality of air passages of 45 different size in said manifold, and means for delivering the primary mixture to the smaller of said passages.
15. A charge forming device for internal combustion engines comprising a carburetor unit provided with means for forming a primary mixture of air and fuel and a manifold associated therewith which is adapted to supply a combustible mixture to the engine intake ports, an air inlet for supplying air to said manifold, a plurality of passages of different size in said manifold, means for delivering the primary mixture to the smaller of said passages, and means for closing the larger of said passages at all speeds below 50 a certain predetermined speed.
16. An intake manifold for an internal combustion engine comprising a plurality of outlet branches adapted to communicate with the engine intake ports, an air inlet admitting air to said manifold, and a plurality of passages formed in said manifold, each of which communicates with said air inlet and with all of the engine ports.
17. An intake manifold for an internal combustion engine comprising a plurality of outlet branches adapted to communicate with the engine intake ports, an air inlet admitting air to said manifold, a plurality of passages formed in said manifold, one of said passages being constantly open and means for closing another of said passages until the engine is operating at a certain predetermined speed.
18. An intake manifold for an internal combustion engine comprising a plurality of outlet branches adapted to communicate with the engine intake ports, an air inlet admitting air to said manifold, a plurality of passages formed in said manifold, one of said passages being constantly open and a normally closed suction operated valve in another of said 55 passages.

sages adapted to be opened when the engine is operating at a certain predetermined speed.

19. An intake manifold for an internal combustion engine comprising a plurality of outlet branches adapted to communicate with the engine intake ports, an air inlet admitting air to said manifold and a partition in said manifold dividing it into two passages, each of which communicates with said air inlet and with all of said intake ports.

10 In testimony whereof I hereto affix my signature.
